his Attorney.

UNITED STATES PATENT OFFICE.

CHARLES JOSEPH LANGENBACH, OF DORCHESTER, IOWA, ASSIGNOR OF ONE-HALF TO JACOB F. FORCE, OF MINNEAPOLIS, MINNESOTA.

BOLT..

SPECIFICATION forming part of Letters Patent No. 403,847, dated May 21, 1889.

Application filed January 16, 1889. Serial No. 296,486. (No model.)

To all whom it may concern:

Be it known that I, CHARLES JOSEPH LANGENBACH, a citizen of the United States, and a resident of Dorchester, in the county of Al-
5 lamakee and State of Iowa, have invented certain new and useful Improvements in Door and Sash Fasteners; and I do hereby declare that the following is a full, clear, and exact de-
10 scription of the invention, which will enable others skilled in the art to which it apper-
tains to make and use the same, reference be-
ing had to the accompanying drawings, which
15 form a part of this specification, and in
which—

Figure 1 is a side elevation of a door equipped with my improved fastener. Fig. 2 is a similar view of a window-sash, illustrating my de-
20 vice as applied as a sash-fastener. Fig. 3 is a cross-section through the knob-plate, knob,
25 and its spindle on line xx in Fig. 1. Fig. 4 is a perspective view of the knob-plate and spin-
dle; and Fig. 5 is a perspective view of the
knob and its disk, showing the same in an inverted position.

Like letters of reference denote correspond-
ing parts in all the figures.

This invention relates to devices for oper-
ating the spring bolts or locks of doors and
30 sashes, and has for its object to provide means
for the speedy and simultaneous operation of
two spring-actuated bolts located at opposite
ends of the door, or on opposite sides of a win-
dow-sash, as the case may be.

With this end in view my invention con-
35 sists in the detailed construction and combi-
nation of parts of the operating device, which
will be hereinafter more fully described and
claimed.

In the accompanying drawings, the letter A
40 designates in Fig. 1 a door-easing, and in Fig.
2 a sash-frame. Similarly, B denotes in the
one case a door, and in the other a sliding
sash. The spring locks or bolts, which may be
45 of any desired construction, are located within
boxes C and C', opposite to each other, and
have their inner ends connected to opposite
ends, D and D', of a wire or thin wire cord,
the middle part of which is inserted through
50 perforated guide-studs E and E', fastened
upon the knob-plate F diagonally opposite to
each other.

Upon the middle of plate F is secured the
spindle G, the upper end of which forms a
screw-threaded socket for the insertion of the
knob-screw H. Plate F is also provided with
55 a short stud, I, the function of which will be
described later on.

The knob J has at its lower end a circular
disk, K, having a circumferential groove, L,
and an annular recess or face-groove, M, en-
60 circling the central spindle-bore, N. A series
of equidistant apertures, O, are bored through
the edge-groove L into the annular recess M,
and a portion of the outer rim or flange of the
disk is cut away on the under side, as shown
65 at P. After one end, D, of the operating wire
or wire cord has been fastened to the spring-
bolt of its appropriate lock C, the free end of
the wire is inserted through its appropriate
guide-stud E and then through one of the
70 apertures O in the rim of the disk K. The
wire is then pulled taut, and its middle part
is wound around one side of the central disk-
hub, K', the edge of which is grooved for the
reception of the wire. Next the opposite or
75 free end of the wire is inserted through the
disk-aperture O, which is diametrically oppo-
site to the aperture through which the wire
entered the disk, and after the wire is again
drawn taut its free end D' is fastened in the
80 spring-bolt of its appropriate spring-lock C',
but not until the knob with the wire fastened
in it has been replaced upon its spindle G and
fastened thereon by the knob-screw H.

The function of the short stud I upon the
knob-plate F is to form a stop in turning the
knob, as by giving this a quarter-turn the
shoulders or offsets s, formed by the cut-away
portion P of the disk-flange, will strike against
85 this stud and thereby prevent the knob from
being turned too far in withdrawing the bolts
when it is desired to open the door or sash, as
the case may be. After the knob is again let
go the spring-tension of the bolts, pulling on
90 opposite ends of the wire, will operate to turn
the knob back into its normal position.

It will be seen that the circumferential
groove or channel L, in conjunction with the
perforated guide-studs E and E', guides the
operating-wire as this is being wound par-
tially around the disk in withdrawing the
bolts, while the annular bottom recess, M, af-

for'ds room for that part of the wire which works between the disk and the flat surface of the knob-plate, so that the knob and its disk may be placed flush with the plate, thus giving 5 to the device a neat and finished appearance.

Having thus described my invention, I claim and desire to secure by Letters Patent of the United States—

The combination, with the operating cord 10 or wire having its ends connected to the oppositely-arranged spring locks or bolts, of the operating device consisting of the knob-plate,

guide-studs, spindle, and recessed and apertured knob-disk and knob, constructed and combined to operate in the manner and for the purpose substantially as herein shown and set forth.

In testimony that I claim the foregoing as my own I have hereunto affixed my signature in presence of two witnesses.

CHARLES JOSEPH LANGENBACH.

Witnesses:

JOHN GUNDERSON,
L. COPPERSMITH.
